UNITED STATES PATENT OFFICE.

HYMAN FREEDMAN AND HARRY BORSKY, OF NEW YORK, N. Y.

LOCK.

Application filed August 28, 1926. Serial No. 132,088.

The main object of this invention is to provide an improved type of lock which is adapted to engage a door frame at the top and bottom of the latter.

Another object of the invention is to provide a lock which may be opened from within or without and uses a pair of oppositely disposed and oppositely moving bars to lock a door within a frame. The lock uses the ordinary key cylinder on the outside of the door and is provided with a wing bolt on the inner side, both means being adapted to retract or extend the locking bars out of their keepers or into their keepers in the frame.

The above and other objects will become apparent in the description below, in which characters of reference refer to like-named parts in the drawing.

Referring briefly to the drawing, Figure 1 is a side elevational view of the lock with the cover removed from the casing for the purpose of illustrating the internal operating mechanism.

Figure 2 is a sectional side elevational view of the same, taken on line 2—2 of Figure 1.

Figure 3 is an end elevational view of Figure 1.

Figure 4 is a perspective view of the lock, showing the locking bars in extended position.

Referring in detail to the drawing, the numeral 10 indicates the rectangular bottom of the lock casing. This bottom is integral with a pair of end walls 11 and 12 and additional side walls 13 and 14, which latter join the end walls. The walls and bottom combine to form a rectangular housing in which a relatively large spur gear 15 is mounted. This spur gear is provided with conical depressions 16 which are formed axially and receive conical lugs 16' which latter project from the adjacent faces of the bottom 10 and cover 29. These lugs serve as journals upon which the spur gear is mounted. Said spur gear has no connection with any part of the mechanism lying externally of the lock. The spur gear rotates approximately 90 degrees or less and is provided with teeth 17 around part of its periphery only. These teeth are engaged by similar ones formed on the periphery of a pinion 18, the latter being rotatably mounted within the chamber 19 of the casing immediately below the spur gear 15.

Said pinion is provided with a square axial opening 20 which passes entirely thru its thickness. It is to be noted that the opposing faces of the pinion are provided with flanges which insert in openings in the bottom 10 and cover 29 and serve as centers for rotation of said pinion. This pinion when rotated is adapted to transmit movement to the spur gear 15 thru the medium of the interlocked teeth of the spur gear and said pinion. A round shaft 21 passes partly thru the square opening 20 in the pinion. One end of this shaft is rigidly secured to a plate 22 of a key cylinder 23 whose rotatable barrel within the cylinder is rigidly attached to said plate 22. The cylinder has a housing 24 integral with and surmounting it in which the plungers of the barrel locking mechanism are located. This cylinder has one end covered by a flange 25 which is embedded in a recess 26 of a door plate 27, the latter being mounted on the outside surface of the door 28 by screws which engage the door plate from the opposite side of the door 28. The end 30 of the round shaft 21 projects from the extremity of the latter and is square in cross section, it being noted that the distance between the flats of this square end is greater than the diameter of the round shaft 21 with which the square end is integral. Approximately half of the length of the square end extends into the square opening 20 formed in the pinion and the remaining portion of the length projects from the cover 29. The square end 30 of the shaft 21 has a square sleeve 31 slidably mounted thereon. This square sleeve is provided with a fixed additional sleeve 32 which is slipped into its open end, the additional sleeve being slidable upon the square end 30 and rotatable upon the round shaft section 21. The sleeve 31 has a longitudinal square bore 33 therein in which the round head 35 at the end of the square portion 30 is slidable. Said sleeve has a wing plate 34 at its outer end by which means the sleeve may be slid or rotated upon its complementary parts. Within the square bore 33 of the sleeve, a coil spring 36 is fixed and yieldably urges the sleeve outwardly thru being seated upon the face of the head 35 and engaging at its opposite end a surface rigid in the bore 33 of the sleeve. A resilient finger 50' is mounted on the end wall 12 of the casing within the chamber thereof and its free end is flexible and en-

gages the teeth of the pinion 18 to frictionally retain this pinion in place.

A pair of pins 38 and 39, diametrically opposed to each other, project upwardly from the face of the spur gear 15. The pin 38 is slidable in a slot 40 which extends horizontally across part of the width of a locking bar 41. The lower end of the locking bar 42 is adapted to be extended thru a channel 43 out of the lock and in a downward direction. The remaining pin 39, mounted on the opposite side of the face of the spur gear operates slidably in a widthwise extending slot 44 formed in a locking bar 45, whose end 46 extends out of a channel 47 situated near one corner of the casing. The locking bar 45 is slidable longitudinally into a chamber 19 of the casing and its retractive movement is limited by a stop pin 48. Two of the corners of the casing walls are provided with bosses 49 in which threaded holes 50 are provided which are engaged by screws passing thru suitable openings formed in the cover 29.

This mechanism is adapted to extend the ends 46 and 42 of the locking bars 41 and 45 in opposite directions out of the casing of the mechanism. The bars may be of a length suitable to extend from the center of the upper and lower ends of the door so that the ends 42 and 46 of said bars may be projected into the customary recesses of suitable keepers, said keepers not being shown on the drawing. When a key is inserted into the barrel located in the cylinder 23, the plungers in the housing 24 are normally aligned with the periphery of the barrel as is well known, after which said barrel may then be readily rotated in either direction. As the barrel is rotated, the plate 22 is rotated a corresponding degree, carrying with it the round shaft 21 and the square end 30. As the square end 30 normally carries the sleeve 33, which latter is square in cross section and slidable in the square opening 20 of the pinion gear, the latter is rotated also to a corresponding degree as the barrel in the key cylinder. Rotation of this pinion 18 transmits movement to the spur gear 15 and the pins 38 and 39 describe an arcuate movement and cross from one side of the sleeves 40 and 44 to the opposite ends. As these pins 38 and 39 move longitudinally in either direction, the locking bars 41 and 45 are moved in the same direction as their corresponding pins and are either retracted or extended accordingly as the spur gear is rotated. In this manner, the locking bars 45 and 41 may be retracted or extended thru the means of a key inserted into the barrel of the locking cylinder. In order to extend or retract these locking bars from the opposite side of the door, the wing plate 34 is depressed or pushed inwardly toward the lock so that the addi-

tional sleeve 32 comes in contact with the round portion of the shaft 21. This permits the sleeve 33 to be rotated independently of the shaft 21 and as the sleeve 33 is square in cross section and slidably fits into the square opening 20 of the pinion, the latter and spur gear may be rotated accordingly as the wing plate 34 is rotated. When inward pressure on the wing plate 34 is released the spring 36 again extends the sleeve 33 so that the additional sleeve 32 integral with the first-named sleeve will again slide upon the faces of the square end 30 so that the locking mechanism is normally in a position which permits the locking bars to be either extended or retracted by means of the key.

It is to be noted that certain changes in form and construction may be made without departing from the spirit and scope of the invention.

We claim:

1. In a lock, a casing, a spur gear rotatable in said casing, a pinion in the casing meshing with said spur gear, locking bars extending from said casing and being extensible and retractable out of said casing, diametrically opposed pins on opposite sides of said spur gear, said locking bars having slots therein, said pins engaged in said slots, the spur gear when rotated arcuately extending or retracting said locking bars, and means for independently actuating said locking bars from either side of a door.

2. In a lock, a casing, a spur gear rotatable in said casing, a pinion in the casing meshing with said spur gear, locking bars extending from said casing and being extensible and retractable out of said casing, diametrically opposed pins on opposite sides of said spur gear, said locking bars having slots therein, said pins engaged in said slots, the spur gear when rotated arcuately extending or retracting said locking bars, said slots extending widthwise in the locking bars, the pins on said spur gear passing from one end of said slots to the opposite end when said spur gear is rotated in retracting or extending said locking bars, and cooperating means extending from opposite sides of the casing for independently actuating said spur gear from opposite sides of a door.

3. In a lock, a casing, a spur gear rotatable in said casing, a pinion in the casing meshing with said spur gear, locking bars extending from said casing and being extensible and retractable out of said casing, diametrically opposed pins on opposite sides of said spur gear, said locking bars having slots therein, said pins engaged in said slots, the spur gear when rotated arcuately extending or retracting said locking bars, said slots extending widthwise in the locking bars, the pins on said spur gear passing from one end

- of said slots to the opposite end when said spur gear is rotated in retracting or extending said locking bars, cooperating means extending from opposite sides of the casing
- 5 for independently actuating said spur gear from opposite sides of a door comprising a key cylinder mounted on one side of said casing, a round shaft extending from said key cylinder actuated thereby into the casing, said pinion having a square opening therein larger than said shaft, a sleeve slideable in the square opening of said pinion and rotatable on said shaft, and means mutually cooperative on said shaft and sleeve
- 10 for normally locking said sleeve on said shaft.
4. In a lock, a casing, a spur gear rotatable in said casing, a pinion in the casing meshing with said spur gear, locking bars
- 20 extending from said casing and being extensible and retractable out of said casing, diametrically opposed pins on opposite sides of said spur gear, said locking bars having slots therein, said pins engaged in said slots,
- 25 the spur gear when rotated arcuately extending or retracting said locking bars, said

slots extending widthwise in the locking bars, the pins on said spur gear passing from one end of said slots to the opposite end when said spur gear is rotated in re- 30

extending or extending said locking bars, co- operating means extending from opposite sides of the casing for independently actuating said spur gear from opposite sides of a door comprising a key cylinder mounted 35

on one side of said casing, a round shaft ex- tending from said key cylinder actuated thereby into the casing, said pinion having a square opening therein larger than said shaft, a sleeve slideable in the square opening 40

of said pinion and rotatable on said shaft, said shaft being circular in cross section, a square end integral with and projecting from said shaft, said sleeve being slideable on said square end and when so positioned lock- 45

ing the sleeve rotatably on said square end, and means for normally causing the sleeve to engage the square end of said shaft.

In testimony whereof we affix our signatures.

HYMAN FREEDMAN.
HARRY BORSKY.
